US0D1024492S

(12) **United States Design Patent** (10) **Patent No.:** **US D1,024,492 S**
(45) **Date of Patent:** **** Apr. 30, 2024**

(54) **RUNNING VEST**

(71) Applicant: **Xinyi Fu**, Foshan (CN)

(72) Inventor: **Xinyi Fu**, Foshan (CN)

(**) Term: **15 Years**

(21) Appl. No.: **29/927,212**

(22) Filed: **Feb. 2, 2024**

(51) LOC (14) Cl. **02-02**

(52) U.S. Cl.

USPC **D2/829**

(58) **Field of Classification Search**
